ATTORNEY.

UNITED STATES PATENT OFFICE.

WILLIAM HALKET, OF HOLYOKE, MASSACHUSETTS, ASSIGNOR TO L. D. VAN VALKENBURG, OF HOLYOKE, MASSACHUSETTS.

BUTTON-HOLDING RETAINER.

1,412,938.

Specification of Letters Patent. Patented Apr. 18, 1922.

Application filed May 27, 1919, Serial No. 300,120. Renewed February 10, 1922. Serial No. 535,614.

To all whom it may concern:

Be it known that I, WILLIAM HALKET, a citizen of the United States of America, and resident of Holyoke, in the county of Hampden and State of Massachusetts, have invented certain new and useful Improvements in Button-Holding Retainers, of which the following is a full, clear, and exact description.

10 This invention relates to improvements in retainers for pencils, pens and other writing instruments, and its leading object is to provide a retainer with simple means for locking the base of a button or display device thereto, in such manner that the locking connection will not be observable from the exterior of the retainer.

Another object of the invention is to provide a retainer with locking means of this character which will permit of the easy and quick assemblage of the display device on the head of the retainer.

With the above and other objects in view the invention consists in certain new and useful constructions, combinations, and arrangements of parts, clearly described in the following specification and fully illustrated in the accompanying drawings, in which:

30 Fig. 1 is a front elevation of my improved retainer.

Figure 2 is a front elevation of the retainer with the button removed.

Figure 3 is a side elevation thereof.

35 Fig. 4 is a side elevation of the retainer band and a vertical sectional view of a button connected therewith.

Figure 5 is a side elevation of a button base.

40 Referring to the accompanying drawings illustrating the practical embodiment of my invention, 5 designates the pencil or pen clamp or gripping band and 6 the pocket or garment gripping or holding bar, which is provided with the usual ball terminal 7. The band, bar and ball terminal may be of any construction.

50 The band 5 is formed with a central face projection 5^a and has the button locking tongue 8 stamped therefrom, the drawing showing the free end of the tongue disposed near the top portion of the projection or extension 5^a. The locking tongue 8 is formed on the band 5 so that it will be slightly off-set therefrom, as shown in Fig. 2, and the

free end or terminal portion of said tongue is slightly curved outward from the band 5 so as to provide a slight clearance for the admission of the metal of the button base. The tongue 8 is also formed with a slight indentation 8^a.

The base 9 of the button or display device to be attached to the retainer is formed with a small slot 9^a to admit the tongue 8 and with a small opening 9^b to receive the indented portion 8^a. The base 9 is placed adjacent the band 5 and the free terminal portion of the tongue 8 is forced into the opening 9^a and across the inner face of the base 5 so that the indented portion 8^a will snap into the opening 9^b, thus locking the base to the band 5. The face 10 of the button is then attached by any suitable method to the base 9, thus covering the tongue 8 and wholly concealing the locking connection.

By means of my invention various kinds of advertising or display buttons or emblems may be readily attached to the band of the retainer and secured locked against movement or removal.

The locking connection provides an interlocking connection between the band or head of the retainer and the base or back of the button or emblem. The indented portion 8^a is designed to snugly fit in the opening 9^b, so that the tongue 8 has a two-point bearing on said base which will insure a non-movable connection between the base and the retainer. The face of the button may be crimped on the edge of the base, or otherwise secured in place, and when so secured the tongue 8 and its connection with the base will be completely concealed from observation.

The construction is such as to permit of quick assemblage of the advertising buttons or articles on the head or band of the retainer.

The buttons or display devices or emblems are made up with backs or bases provided with the small slot to receive the tongue and another small slot or recess or the like to receive the off set portion of the tongue, so that a completely assembled button may be quickly and easily slipped on the tongue of the retainer and positively locked in place.

Having described my invention I claim:

1. A retainer for writing instruments having an encircling band formed with a spring tongue adapted to enter an opening in a but-

ton and provided with an indentation adapted to have interlocking engagement with the button to prevent displacement of the button on said band.

5. 2. A retainer for writing instruments and the like consisting of a band having a spring tongue stamped thereon and formed with a terminal indentation and a button base having means adapted to be interlocked with 10 said terminal indentation.

15. 3. The combination of a base member for buttons having spaced openings, of a retainer for writing instruments and the like having a spring tongue adapted to enter one of said openings and an indentation or the like to engage the other opening and hold 20 said base member against relative movement on said tongue and band.

4. The combination with a base member 25 for buttons and the like of a retaining element having a spring tongue adapted to have a sliding interlocking connection with the base member.

5. In combination, a retainer having a

gripping bar and a spring tongue thereon, 25 said tongue having an offset portion located near one end thereof, and a base having an opening to receive the tongue, said opening being located in one side thereof said base being provided with means spaced from said first opening to receive the offset portion of 30 said tongue.

6. In combination, a retainer provided with a gripping bar, and a writing instrument clasping device, said retainer being 35 provided with a spring tongue having an offset portion, and a base for a button having an opening located near one side thereof through which the tongue may be extended and means located distantly from 40 said opening to receive said offset portion, said tongue being adapted by its spring tension to hold said base snugly against said device and said offset portion being adapted to prevent movement of said base on said 45 tongue.

WILLIAM HALKET.
